UNITED STATES PATENT OFFICE

116,805

DESIGN FOR A PARKING METER

Ben Reznek, Washington, D. C.

Application February 2, 1939, Serial No. 82,733

Term of patent 7 years

To all whom it may concern:

Be it known that I, Ben Reznek, a citizen of the United States, residing at Washington, in the District of Columbia, have invented a new, original, and ornamental Design for Parking Meters, of which the following is a specification, reference being had to the accompanying drawing, forming part thereof.

Fig. 1 is a front elevation of a parking meter showing my new design.

Fig. 2 is a side elevation thereof.

Fig. 3 is a top plan view thereof.

The lettering appearing on the figures is merely representative.

I claim:

The ornamental design for a parking meter, as shown and described.

BEN REZNEK.
